UNITED STATES PATENT OFFICE.

JAMES C. POTTER AND JOHN JOHNSTON, OF PAWTUCKET, RHODE ISLAND,
ASSIGNORS TO POTTER AND JOHNSTON MACHINE COMPANY, OF PAWTUCKET, RHODE ISLAND.

WORK-TABLE FOR SHAPING-MACHINES.

SPECIFICATION forming part of Letters Patent No. 719,255, dated January 27, 1903.

Application filed January 29, 1902. Serial No. 91,773. (No model.)

To all whom it may concern:

Be it known that we, JAMES C. POTTER and JOHN JOHNSTON, of Pawtucket, in the county of Providence, and in the State of Rhode Island, have invented certain new and useful Improvements in Work-Tables for Shaping-Machines; and we do hereby declare that the following is a full, clear, and exact description thereof, reference being had to the accompanying drawings, in which—

Figure 1 is a side elevation of a shaping-machine provided with a work-table embodying our invention. Fig. 2 is a front elevation thereof. Fig. 3 is a detail view in longitudinal section of the work-table, and Fig. 4 is a like view in cross-section.

Letters of like name and kind refer to like parts in each of the figures.

The object of our invention is to provide a work-table for shaping and other machines which will have capacity for adjustment to add to the variety of the work that the machine may do; and to this end our invention consists in the work-table having the features of construction substantially as hereinafter specified.

We illustrate our work-table applied to our shaping-machine, which forms the subject of United States Patent No. 649,175, granted May 8, 1900, the work-holder A being mounted upon a horizontally-movable carriage B and the latter upon a vertically-movable carriage C. As in the machine of the patent, the work-holder A is hollow, it having a cylindrical opening by which it is mounted upon a cylindrical bearing or trunnion b, that projects horizontally from the carriage B, upon which the holder may be revolved to present the work clamped to or held upon it at various angles. For so revolving the work-holder the trunnion has worm-teeth D in its periphery, meshing with which is a worm E on a shaft F, mounted in bearings on the holder A, the shaft at one end having an angular or polygonal head f for the application of a wrench or handle for turning the shaft. As in the work-table of the patent referred to, there is a plate or head G at the outer end of the trunnion which overlaps the end of the

work-holder and is adapted to be clamped thereto to hold it from rotation by a bolt H, which engages a nut b', attached to or integral with the trunnion.

For accurate adjustment of the work-holder a scale and index are provided, as in the case of the work-table of the machine of the patent before mentioned.

Besides presenting the work at an angle by the revolution of the holder on the trunnion, we provide for presenting it at an angle by hinging or pivoting to one of the sides of the holder a plate I, having clamping-grooves or other means for the attachment of the work thereto, the axis of the pivot or hinge being at right angles to the trunnion-axis. The plate I is placed between a pair of flanges or ledges a and a, and it is hinged thereto by a pivot-pin K passing through each ledge and screwed to the plate. Said flanges or ledges firmly support the plate against lateral movement. For tilting and supporting the plate in the position to which it may be tilted a screw L is mounted in a threaded lug or bracket g on the inner side of the head G, the outer end of which engages a bearing lug or projection i, secured to the under side of the plate, the work-holder having a slot a' to accommodate said lug i, and the trunnion being provided with a hole b² for the passage of the screw. For revolving the screw it has at its inner end a spiral gear M, with which engages a like gear-wheel N on the inner end of a horizontal shaft O, journaled in the head G and having outside the latter an angular or polygonal head o for the application of a wrench or handle for turning the shaft.

It will be observed that the plate-tilting mechanism is housed by the work-holder and trunnion. The side of the work-holder to which the plate I is pivoted is parallel with the axis of the work-holder, and the plate when it is desired to use it with work that requires to be supported in a plane parallel with the axis of the work-holder rests solidly upon said side, so that when it is necessary to place the plate in proper position for such work it is merely lowered until it strikes such side of the work-holder, no careful adjust-

ment, which of course would require time, being necessary to place the plate in position, for it will be known to be in position when it is lowered into contact with the side of the 5 work-holder.

The mechanism for tilting the plate is very simple, and as it is not connected to the plate it does not interfere with the rotation of the work-holder, it being necessary when the latter is to be turned merely to see that the screw L does not protrude beyond the trunnions. The various angular heads for the application of a wrench or handle are of the same size and shape, so that one wrench or 15 handle may answer for all.

Though we show our work-table applied to our patented shaper, it is to be understood that we do not restrict ourselves to its use with said machine or any particular machine.

20 Having thus described our invention, what we claim is--

1. In a work-table, the combination of a hollow work-holder having a tilting work-holding plate, and plate-tilting means within the 25 work-holder.

2. In a work-table, the combination of a hollow work-holder having a tilting work-holding plate, and plate-tilting mechanism comprising a part passing from within the work-holder through an opening in the wall of the work-holder and engaging the plate.

3. In a work-table, the combination of a hollow work-holder having a tilting work-holding plate, and plate-tilting mechanism comprising a screw that passes through an opening in the wall of the work-holder to act on the plate.

4. In a work-table, the combination of a rotatable work-holder having a side parallel 40 with its axis of rotation, a work-holding plate pivoted to such side and having a plane surface next the latter that rests in contact therewith when the plate is placed in a position parallel with the work-holder axis, and means for tilting said plate.

5. In a work-table, the combination of a hollow, rotatable work-holder having a side parallel with its axis of rotation, a work-holding plate pivoted to such side and adapted to rest 50 thereon when placed in a position parallel with the work-holder axis, and means within the work-holder for tilting said plate.

6. In a work-table, the combination of a

work-holder having a tilting work-holding plate, the work-holder having flanges on opposite sides of the plate and extending from end to end of the plate and between which at one end said plate is pivoted, and plate-tilting mechanism.

7. In a work-table, the combination of a rotatable work-holder, a tilting work-holding plate on said work-holder, plate-tilting mechanism, and a support for such mechanism, relative to which the work-holder turns, substantially as and for the purpose described. 60

8. In a work-table, the combination of a rotatable work-holder a tilting work-holding plate on said work-holder, plate-tilting mechanism comprising a screw engaging but unconnected with the plate, and a support for 70 such mechanism relative to which the work-holder turns, substantially as and for the purpose described.

9. In a work-table, the combination of a work-holder having a tilting work-holding 75 plate, a support on which said work-holder is mounted to turn, a clamping-head for the work-holder, and plate-tilting mechanism mounted on such head, substantially as and for the purpose described.

80 10. In a work-table, the combination of a work-holder having a tilting work-holding plate, a trunnion on which said holder is mounted, a clamping - head for the work-holder, and a screw engaging a threaded projection on said head and adapted to tilt the plate, substantially as and for the purpose described.

11. In a work-table, the combination of a work-holder having a tilting work-holding 90 plate, a trunnion on which said work-holder is mounted, a clamping-head for the work-holder, a screw engaging a threaded projection on said head, adapted to act upon, but unconnected with the plate, an operating-shaft, and gearing between the latter and the screw, substantially as and for the purpose described.

95 In testimony that we claim the foregoing we have hereunto set our hands this 31st day 100 of August, A. D. 1901.

JAMES C. POTTER.
JOHN JOHNSTON.
